VERTICAL LIFT AIRPLANE

George Francis Myers, Jackson Heights, N.Y.
Application October 14, 1957, Serial No. 48,087

Term of patent 14 years

(Cl. D71—1)

T19.2.

T19.3.

Fig. 1 is a front elevational view of a vertical lift airplane embodying my new design:

Fig. 2 is a side elevational view thereof: and

Fig. 3 is a top plan view thereof.

I claim:

The ornamental design for a vertical lift airplane, substantially as shown.
